Primary Examiner — Lauren D McVey

(57) **CLAIM**

The ornamental design for printer stand as shown and described.

DESCRIPTION

1.1 is a top plan view of a printer stand, showing our new design;

1.2 is a bottom plan view thereof;

1.3 is a rear elevation view thereof;

1.4 is a front rear elevation view thereof;

1.5 is a left side elevation view thereof;

1.6 is a top, right side perspective view thereof; and

1.7 is a right side elevation view thereof.

The broken lines in the figures are for the purpose of illustrating portions of the printer stand and form no part of the claimed design.

1 Claim, 7 Drawing Sheets
